US00D874329S

(12) **United States Design Patent** (10) **Patent No.:** **US D874,329 S**
(45) **Date of Patent:** **** Feb. 4, 2020**

(54) **GEMSTONE**

(71) Applicant: **BONOLI S.R.L.**, Forlì' (IT)

(72) Inventor: **Massimiliano Bonoli**, Forlimpopoli (IT)

(73) Assignee: **BONOLI S.R.L.**, Forlì (IT)

(**) Term: **15 Years**

(21) Appl. No.: **29/671,298**

(22) Filed: **Nov. 26, 2018**

Related U.S. Application Data

(62) Division of application No. 29/600,161, filed on Apr. 10, 2017.

(30) **Foreign Application Priority Data**

Oct. 10, 2016 (EM) 003412881

(51) **LOC (12) Cl.** **11-01**

(52) **U.S. Cl.**

(57) **CLAIM**

I claim, the ornamental design for a gemstone, as shown and described.

DESCRIPTION

The file of this patent contains at least one photograph executed in color. Copies of this patent with color photograph(s) will be provided by the Office upon request and payment of the necessary fee.

FIG. 1 is a perspective view of a gemstone showing a first embodiment of my new design;

FIG. 2 is a front view thereof, the opposite side view being a mirror image thereof;

FIG. 3 is a bottom view thereof;

FIG. 4 is a left side view thereof, the opposite side view being a mirror image thereof;

FIG. 5 is a top view thereof;

FIG. 6 is a perspective view of the gemstone showing a second embodiment of my new design;

FIG. 7 is a bottom view thereof;

FIG. 8 is a front view thereof, the opposite side view being a mirror image thereof;

FIG. 9 is a left side view thereof, the opposite side view being a mirror image thereof;

FIG. 10 is a top view thereof;

FIG. 11 is a perspective view of the gemstone showing a third embodiment of my new design;

FIG. 12 is a front view thereof, the opposite side view being a mirror image thereof;

FIG. 13 is a bottom view thereof;

FIG. 14 is a left side view thereof, the opposite side view being a mirror image thereof; and,

FIG. 15 is a top view thereof.
